JOURNAL LUBRICATOR

Richard J. Shanahan and Milton D. Pattullo,
Wilmette, Ill.

Application September 4, 1947, Serial No. 772,094

5 Claims. (Cl. 308—91)

1

This invention relates to journal lubricators which are particularly adapted for use in the conventional or standard A. A. R. journal boxes on railroad cars for lubricating the journals of the axles.

At the present time it is customary to fill the journal box with oil-soaked waste, and thus rely upon the oil contained in such waste for proper lubrication of the journal. There are many disadvantages attendant upon the use of such a lubricating means in that threads from the waste may very easily creep between the axle and its bearing. Such a presence of threads is sufficient to cause a hot box.

The use of oil-soaked waste for lubrication in journal boxes is still in current use on railroad cars despite the many efforts in the past to devise effective lubricating means in the form of rollers rolling in a bath of oil and carrying the oil to the journal. Such earlier devices have proven unsatisfactory either from the standpoint of ineffective operation or from the economical view. Those journal lubricators which may have operated satisfactorily have been expensive to install because of the necessity of using a special type of journal box.

The present invention is designed to overcome these earlier disadvantages, as well as the disadvantages present in lubricators currently in use, by the provision of effective lubricating means adapted to be installed in the conventional or standard A. A. R. journal boxes.

An important object of the present invention is to provide a journal lubricator of the character herein described which is effective for lubricating the journal of railroad cars and which may be installed on the standard journal boxes with which all railroad cars are supplied.

Another object of the invention is to provide a journal lubricator to lubricate the journals of railroad cars, which includes a roller mounted on a floating axle below the journal and having main and auxiliary resilient or yieldable means for urging the roller upwardly against the journal.

A further object of the invention is to provide a railroad car journal lubricator which includes a roller located in a bath of oil, and yieldable means for urging the roller against the journal. The yieldable means includes more specifically a leaf spring at each end of the roller and a pair of coiled compression springs also located at each end of the roller, whereby both types of springs cooperate to urge the roller upwardly against the journal.

Still another object of the invention is to pro-

vide a dual form of yieldable supporting means which support a roller and urge the roller against the journal of a railroad car, so that if one of the yieldable supporting means is broken or becomes fractured for any reason, then the other yieldable support may still function to effectively lubricate the journal.

A still further object of the invention is to provide a roller for use in lubricating the journal 10 of a railroad car, which roller is either itself formed of a light weight semi-resilient composition, or which may have a covering of such a resilient material over the surface thereof to thereby provide a cushioning effect between the 15 roller and the journal which is lubricated by it.

Still another object is to provide a roller of a semi-resilient composition, which roller has in its outer surface a series of spiral grooves which act to carry the oil from the oil bath in which the 20 roller is located and distribute the oil over the journal.

Still another and more specific object is to provide a journal lubricator of the character described herein wherein a roller is provided with 25 a cover of a resilient material, the resilient material and the roller having aligned radial openings therethrough to aid in distributing oil over the journal due to the action of centrifugal force.

Other objects and advantages of the invention 30 will become apparent upon reading the following description taken in conjunction with the accompanying drawings in which:

Fig. 1 is a vertical longitudinal sectional view through a standard journal box showing the 35 journal and roller in elevation;

Fig. 2 is a horizontal sectional view taken substantially along the plane of line 2—2 of Fig. 1;

Fig. 3 is an end elevational view of the journal 40 box with parts broken away and shown in section;

Fig. 4 is a fragmentary vertical sectional view taken substantially along the plane of line 4—4 of Fig. 1.

Referring now more particularly to the drawings, there is illustrated a portion of the axle 1 of a railroad car which has the journal 2 at its end extending into the journal box, generally indicated at 3. The journal box shown is of the conventional and standard type having at its inner end the spaced partitions 4 and 5 with aligned 45 openings 6 therethrough to receive the car axle 1. A dust guard 7 of any suitable construction surrounds the axle and has its peripheral edges extending into the space between the partitions 4 and 5.

Still another object of the invention is to pro-

The outer end of the journal box is provided with the usual gate or door 8 pivotally mounted as at 9 at its upper end to the top of the journal box. The journal 2 has the usual bearing and bearing cap at its upper side which are common in journal box constructions.

The lubricator of the present invention embodies a roller 10 which is preferably of a tubular construction, mounted on an axle 11 and adapted to rotate on the bearings 12. In the form of the invention shown herein, the roller 10 has a covering 13 of a composition material which is both light weight and semi-resilient to thereby form a cushion between the roller 10 and the journal 2. If desired, the entire roller may be formed of this semi-resilient material. The material used is preferably oil, heat, and wear-resistant and the composition which has been found to be most successful thus far in actual practice is a synthetic rubber composition.

The roller 10 and covering 13 have a plurality of aligned radial openings 14 therein for the purpose of distributing oil over the surface of the journal by means of centrifugal force, the oil being thus distributed from the inside of the roller 10. To further aid in evenly distributing the oil over the surface of the journal, the covering 13 is provided with a plurality of spiral grooves 15 adapted to pick up the oil from the bath in the bottom of the journal box and carry it upwardly for distribution over the journal.

Another and important feature of the invention lies in the means for mounting the roller so that it is constantly maintained in contact with the underside of the journal. Resilient means are provided for this purpose in the form of a leaf spring 16 located one at each end of the roller 10. The form and construction of the leaf spring 16 is an important consideration to the effective functioning of the lubricator. The leaf spring is continuous and has one end 17 thereof extending in a substantially horizontal plane in alignment with the end of the axle 11. This end of the leaf spring is then curved as at 18 to partially surround the end of the axle 11 and then terminates in a short horizontal portion 19. The other end 20 of the spring 16 also extends toward the end of the axle 11, is curved upwardly as at 21 to partially surround the other side of the axle 11 and then terminates in a short horizontal portion 22. The terminal portion 22 abuts against the part 17, and the terminal portion 19 abuts upwardly against the horizontal part 20 of the spring 16. Bolts 23 then secure the two ends in place as shown in Fig. 3.

Each of the ends of the leaf spring 16 is then curved downwardly and inwardly as at 24 and is connected by an integral intermediate section 25. The intermediate section 25 preferably bears downwardly against the upper flat surface of an elongated supporting bar 26 which, in turn, is fastened to the bottom of the journal box by means of the bolts 27. It will be noted that the holes through which the bolts 27 pass are the only modification which need be made in the standard journal box.

The leaf spring just described is the main yieldable means which supports the axle 11 and yieldably holds the roller 10 upwardly against the journal 2. The form of this leaf spring is such that it will hold the oily roller in place against the journal at all times, even during impact of the axle against it due to shock, which occurs during the coupling and uncoupling of cars, and particularly freight cars. It will be noted that

the roller will be held against the journal regardless of the direction of impact of the axle against the roller due to the novel construction thereof.

Auxiliary springs in the form of coiled compression springs 28 are also utilized in conjunction with the leaf springs 16 to aid in urging the roller upwardly against the journal. It is preferred that two of the coiled compression springs 28 be located at each end of the roller and are so positioned as to bear upwardly at their upper ends against the terminal portions of the leaf spring 16 and downwardly at their lower ends against the horizontal intermediate portion 25 of the leaf spring. The provision of these coiled springs is an important consideration from the standpoint of safety. The shock of coupling and uncoupling railroad cars may be great enough to fracture the leaf spring 16. If this occurs, then the coiled compression springs 28 are still sufficiently strong to maintain the oily roller in contact with the journal so that proper lubrication will be continued and thus prevent the occurrence of a hot box.

In actual practice and under ordinary conditions the leaf spring 16 will function properly without breaking, but in the shock of coupling and uncoupling, the axle housing may be forced to one side or the other, or it may move upwardly as much as $\frac{1}{8}$ of an inch with respect to the axle. It is under such conditions as this that the leaf spring may fail, but under the provisions of the present invention proper lubrication may still be obtained due to the presence of the coiled springs 28.

It has been found that the combination and co-operation of the two types of springs at each end of the roller, together with the composition covering over the roller, the radial holes and spiral grooves, all contribute materially to the effective operation of the journal lubricator of the present invention. This lubricator has been found to be efficient in use and is extremely economical to install because of its ability to be used in the standard journal boxes now in use merely by boring two holes in the bottom of the journal box.

Changes may be made in the form, construction and arrangement of parts from that disclosed herein without in any way departing from the spirit of the invention or sacrificing any of the attendant advantages thereof, provided, however, that such changes fall within the scope of the claims appended hereto.

The invention is hereby claimed as follows:

1. A journal lubricator adapted for use in the standard journal boxes of railroad cars, comprising a tubular roller mounted for rotation on a horizontal axle below the journal, a resilient covering over the surface of said roller to form a cushion between the roller and the journal, said covering having a plurality of radially disposed openings therethrough, a like plurality of radial openings in said roller in alignment with the openings in said resilient covering, whereby oil within said roller will be thrown outwardly against the journal by centrifugal force, a leaf spring at each end of said roller, each of said springs having overlapping ends secured to the axle of said roller and having a portion bearing downwardly against the bottom of the journal box, a pair of vertically disposed auxiliary coiled compression springs at each end of said roller secured at their upper ends to the leaf spring with which they are associated and also bearing downwardly against the bottom of the journal

box, whereby both the leaf springs and the coiled springs cooperate to urge said roller upwardly against the underside of the journal, and a plurality of spiral grooves in the surface of said resilient covering to more effectively distribute and carry oil to the journal.

2. A journal lubricator adapted for use in the standard journal boxes of railroad cars, comprising a roller mounted for rotation on a horizontal axle below the journal, a resilient covering over said roller to form a cushion between the roller and the journal, a continuous leaf spring at each end of said roller, each of said springs having overlapping ends surrounding the axle of said roller and secured together, a portion of said spring also bearing downwardly against the bottom of the journal box, a pair of vertically disposed auxiliary coiled compression springs at each end of said roller secured at their upper ends to the leaf spring with which they are associated and bearing downwardly against the bottom of the journal box, whereby both the leaf springs and the coiled springs cooperate to urge said roller upwardly against the underside of the journal, and a plurality of spiral grooves in the surface of said resilient covering to more effectively distribute and carry oil to the journal.

3. A journal lubricator adapted for use in the standard journal boxes of railroad cars, comprising a roller mounted for rotation on a horizontal axle below the journal, a resilient covering over said roller to form a cushion between the roller and the journal, a leaf spring at each end of said roller secured to the axle of said roller and bearing downwardly against the bottom of the journal box, and a pair of vertically disposed auxiliary coiled compression springs at each end of said roller secured at their upper ends to the leaf spring with which they are associated and bearing downwardly against the bottom of the journal box, whereby both the leaf springs and the coiled springs cooperate to urge said roller

upwardly against the underside of the journal and distribute oil thereto.

4. A journal lubricator adapted for use in the standard journal boxes of railroad cars, comprising a roller mounted for rotation on a horizontal floating axle below the journal, a leaf spring at each end of said roller secured to the axle of the roller and bearing downwardly against the bottom of the journal box to thereby urge said roller upwardly against the journal, each of said leaf springs including end portions extending toward each other and passing around opposite sides of said axle, and auxiliary spring means cooperating with said leaf springs for also urging said roller upwardly against the journal.

5. A journal lubricator adapted for use in the standard journal boxes of railroad cars, comprising a roller mounted for rotation on a horizontal floating axle below the journal, a leaf spring at each end of said roller secured at its ends to said axle and curving downwardly to bear intermediate its ends against the bottom of the journal box, and a pair of auxiliary coiled compression springs at each end of said roller secured at their upper ends to the leaf spring with which they are associated and bearing at their lower ends against the intermediate portion of the leaf spring, whereby both springs cooperate to urge said roller upwardly against the journal.
